UNITED STATES PATENT OFFICE.

AUGUST TILCH, OF LEWISTON, MAINE.

SHUTTLE-BINDER.

No. 880,602.

Specification of Letters Patent.

Patented March 3, 1908.

Application filed March 14, 1907. Serial No. 362,272.

To all whom it may concern:

Be it known that I, AUGUST TILCH, a citizen of the United States, residing at Lewiston, in the county of Androscoggin and State of Maine, have invented new and useful Improvements in Shuttle-Binders, of which the following is a specification.

My invention relates to improvements in shuttle binders. It is equally applicable to 10 single or drop boxes.

In the drawings herewith accompanying and making part of this application, Figure 1 is a top plan view of a drop box showing my improved binder in position holding a shuttle, 15 parts being broken out; Fig. 2 is a side elevation of the same, one binder only being shown; Fig. 3 is an edge view of my improved binder for use in a single loom and Fig. 4 is a transverse sectional view of a portion of Fig. 1 20 taken on line A—A.

Same letters of reference refer to like parts.

My improved binder is adapted to be pivotally attached to the lay and consists of an outside body part A and an inside yielding projection B, the yielding projection being formed by a kerf C entering the binder from a point near the pivoted end C. My improved binder is also provided with means for yieldingly supporting the free end of the 30 projection B independently of the body part. I have illustrated a single form of yieldingly supporting the projection B, but any means of yieldingly supporting the projection B is within the spirit and scope of my invention. 35 As illustrated, I provide a post D passing loosely through the part A and engaging the projection B as seen in Figs. 1 and 3. A spring E is attached to the lay or shuttle box and bears against the end of post D or 40 against an intermediate keeper F which rests loosely against the outside of the part A and is adapted to hold the post from falling out when the spring is removed for any purpose but when in position permits the 45 post to move in the body whereby the projection of the binder is supported by the spring through the motion of said post. The spring is bent so as to pass across the outside of the binder and extends up slightly on each 50 edge as seen at G on one edge and in dotted lines on the other edge at G', to prevent lateral movement of the binder. The binder may be also provided with a flexible strap H 55 beginning at or near the impact end of the binder and extending across the entrance to

the kerf and attached to the other end of the shuttle as seen at I. This strap may be made of leather or any suitable material and lessens the wear on the shuttle. The end of the shuttle binder may have a leather covering 60 as seen at J, if desired, cushioning the end of the shuttle binder where it strikes the shuttle box and protector finger.

In adapting my improved binder for use in drop boxes I provide a supporting strap 65 K having at one end an eye through which the pivot pin L passes and the other end M extending along the outer face of the binder and held in place by a bolt N which passes through the strap and through the binder 70 and may pass through the strap H, if desired, all as seen at Fig. 1. The binder is made adjustable relative to the shuttle by increasing or diminishing the thickness of the intermediate keeper F or one or more 75 washers may be used in place of the keeper.

In operation the first impact of the shuttle is against the inclined face of the binder; it then passes up over the inclined face, forcing the binder outwardly sufficiently to give 80 entrance to the shuttle. As the shuttle enters it strikes the yielding projection B. The part D and the yielding spring E hold the shuttle with a constant but yielding tension thereby preventing any rebound, which 85 often occurs where the shuttle binder is solid at the inner end because there is always a certain amount of vibration to the binder which of course at times frees the shuttle temporarily from the holding effect of the 90 binder, allowing the shuttle to rebound. It will be noted that the projection B operates partly independently of the body part A. It will be noted that the swell on the outer end of the binder may extend further back 95 to the pivot end than in other binders because the binder is elastic toward the pivoted end. This affords an easy entrance to the shuttle.

The advantages of my improved binder 100 are that it is light, simple in construction, the inner part holding the shuttle with a constant tension while the outer part is vibrating and it is easily adjustable to fit shuttles of slightly varying size or shuttles, 105 which are worn in use.

Having thus described my invention and its use I claim:—

A shuttle binder comprising a body part and a yielding projection spaced apart there- 110

from a portion of its length, a post adapted to support the free end of the projection and to register through the body part and a spring mounted independently of the binder 5 and adapted to yieldingly support said post.

In testimony whereof, I have signed my name to this specification in presence of two

subscribing witnesses this 7th day of March, 1907.

AUGUST TILCH.

In presence of—

EMIL DICK,

ROBERT BYR.
